[57] CLAIM

The ornamental design for a telephone message holder
clip, as shown and described.

DESCRIPTION

FIG. 1 is a top, side, rear perspective view of a telephone
message holder clip illustrating my new design;

FIG. 2 is a front elevational view thereof;

FIG. 3 is a side elevational view thereof, the opposite
side being a mirror image thereof;

FIG. 4 is a top plan view thereof; and,

FIG. 5 is a bottom plan view thereof.

FIG. 1

FIG. 2

FIG. 3

FIG. 4

FIG. 5
